KNITTING MACHINE NEEDLE

Arthur Currier, Penacook, N. H., assignor to Acme Knitting Machine & Needle Company, Franklin, N. H., a corporation of New Hampshire

Application February 28, 1934, Serial No. 713,328

6 Claims. (Cl. 163—5)

This invention relates to knitting machine needles of the latch type and more especially to the so-called "rivetless" needles.

As is well understood by those skilled in this art, the latch of a knitting machine needle usually is mounted on a pivot which is either threaded through the walls of the needle shaft or body, or is riveted to them. In using needles of this character, especially those of the smaller sizes and which are commonly employed in knitting fine goods, such as silk hosiery, it occasionally happens that the pivot of the needle latch will work loose sufficiently to allow the end of the pivot to project beyond the outer surface of the needle. When this happens such a projecting end will catch a loop of thread and produce a flaw in the work. With a view to preventing accidents of this character, it has been proposed heretofore to avoid the use of a separate pivot and to form short studs projecting from the opposite walls of the latch slot into the pivot hole in the latch, these studs cooperating to perform the functions of a pivot. This expedient has proved useful in some sizes and styles of needles. A common objection to it, however, is the fact that if the latch is tipped or bent laterally, it is very likely to spring apart the two walls of the slot in which it is located and to snap out of place.

The present invention aims to improve the construction and methods of manufacture of rivetless knitting machine needles with a view to overcoming the difficulty above described and providing a construction which will be more reliable and will have better wearing qualities.

The nature of the invention will be readily understood from the following description when read in connection with the accompanying drawing, and the novel features will be particularly pointed out in the appended claims.

In the drawing,

Figure 1 is a side elevation of a knitting machine needle of the general type with which this invention is concerned;

Fig. 2 is a sectional view on substantially the line 2—2, Fig. 1, but showing the parts on a much larger scale; and

Figs. 3 and 4 are views similar to Fig. 2 but illustrating steps in the method of manufacture of a needle in accordance with this invention.

In making such a needle as that illustrated in Figs. 1 and 2, the shaft or body 2 may be made in any suitable or convenient manner. In a typical process the manufacturing operations on the shaft are completed, and the hook 3 is bent into its final shape, the slot 4 for receiving the latch

being formed at any convenient point in the process. After the various manufacturing operations on the latch have been completed, including the drilling of the hole 7, Fig. 3, to take the latch pivot, the latch and the shaft are assembled in the proper relationship with the shank 6 of the latch correctly positioned in the slot 4. These parts are located, as for example by means of a suitable jig or fixture, in the correct relationship to two punches 8 and 9 which are moved toward each other and stopped when their ends have arrived at predetermined points. The punches reciprocate toward and from each other in a path coincident with their own axes, and the latch and needle are so positioned with reference to them, that the hole 7 in the latch shank is coaxial with the punches. Consequently, when they are moved toward each other to substantially the positional relationship illustrated in Fig. 4, they force inwardly sections of the walls or "cheeks" 5 of the latch at opposite sides of the slot 4, projecting these portions of the metal into the hole 7 where the two sections of metal so displaced 10 operate to form a pivot for the latch. These sections are indicated at 10 and 12, respectively. It 15 will be observed that the end faces of the tips *a* and *b* of the punches 8 and 9 are disposed diagonally with reference to their axes and to that of the hole 7 in the latch. Consequently, the sections 10 and 12 of the metal punched from the 20 cheeks of the needle body are similarly disposed or inclined. These sections thus overlap each 25 other in the hole 7, as clearly shown in Fig. 4, and they abut against each other along a plane 30 which is parallel to the two end faces of the punch tips *a* and *b*. Both of the sections 10 and 12 thus 35 extend across the median plane of the latch so that there is little likelihood of springing the cheeks far enough apart to release the latch.

Preferably the tips *a* and *b* of the punches 8 and 9 are made of circular form in cross-section, but they are tapered slightly, and the end portions of these tips are a few thousandths smaller in diameter than the internal diameter 40 of the hole 7 in the latch shank. Consequently, the metal displaced to form the pivot sections 10 and 12 is moved chiefly in line with the hole 7 and does not flow laterally to any substantial degree. The surfaces of the punches at the junction of the tips *a* and *b* with the main body portions of the punches are tapered, as indicated at 45 *c* and *d*, respectively, and the stroke of the punches is made such that they produce slight 50 counter-sinks in the cheeks, as shown at *c'* and 55 *d'*.

d', Fig. 2, thus avoiding the formation of any burr or rough edge.

The pivot produced in the manner above described completely fills the hole 7 in the latch shank but still remains integral with the shaft so that there is no possibility of the pivot working loose. In addition, any danger of the latch snapping out of place is minimized and, since both sections of the pivot are unusually long for a latch of a given thickness, a longer bearing surface on each section is provided. The necessary play required to make the latch 5 work easily will be produced in the tumbling operation to which the needles customarily are subjected after the manufacturing operations on them have been completed.

While I have herein shown and described a preferred embodiment of my invention, it will be understood that the invention is not limited to embodiment in the exact form shown.

Having thus described my invention, what I desire to claim as new is:

1. A knitting machine needle provided with a latch slot, a latch having a shank located in said slot, said shank having a pivot hole therethrough, and a pivot for said latch comprising parts of the opposite walls of said slot projecting into said hole in the latch shank with said parts overlapping each other in said hole.

2. A knitting machine needle having a latch slot therein and provided with cheeks at opposite sides of said slot, a latch having a shank located in said slot, said shank having a pivot hole therethrough, and a pivot for said latch comprising two pivot sections integral, respectively, with said cheeks, said sections abutting against each other in said slot along a plane disposed diagonally with reference to the axis of said slot.

3. A knitting machine needle having a latch slot therein and provided with cheeks at opposite

sides of said slot, a latch having a shank located in said slot, said shank having a pivot hole therethrough, and a pivot for said latch comprising two pivot sections projecting into said slot and integral, respectively, with said cheeks, both of said sections extending across the median plane of said latch.

4. A knitting machine needle having a latch slot therein and provided with cheeks at opposite sides of said slot, a latch having a shank located in said slot, said shank having a pivot hole therethrough, and a pivot for said latch comprising two pivot sections integral, respectively, with said cheeks, said sections abutting against each other in said slot and having ends diagonally disposed with reference to the median plane of the latch.

5. A knitting machine needle having a latch slot therein and provided with cheeks at opposite sides of said slot, a latch having a shank located in said slot, said shank having a pivot hole therethrough, and a pivot for said latch comprising two pivot sections projecting into said slot and integral, respectively, with said cheeks, said sections being substantially parallel to each other and both disposed diagonally with reference to the axis of said pivot.

6. That improvement in methods of making knitting machine needles, which consists in forcing portions of the opposite walls of the latch slot of a needle body inwardly into the pivot hole of the needle latch, confining said operation to approximately the portions of the metal of the cheeks in line with the latch hole in said slot, and disposing both sections of the pivot so produced in planes parallel to each other but extending diagonally with reference to the axis of said pivot hole.

ARTHUR CURRIER.
